BOTTLE

Jack Goldstein, Bronxville, N.Y., and Marvin Q. Wheeler,
Atlanta, Ga., assignors to The Coca-Cola Company,
Atlanta, Ga., a corporation of Delaware

Filed May 15, 1961, Ser. No. 65,174

Term of patent 14 years

(Cl. D58—8)

The rear and side views of the bottle not shown are the same as the front view shown.

The characteristic feature of our design resides in the combination on the bottle disclosed of a shoulder and heel of identical maximum diameter connected together by an inwardly tapered cylindrical body portion having thereon annular rows of circular indentations of increasingly greater diameters upwardly from the base or heel portion, all as shown.

We claim:

The ornamental design for a bottle, as shown and described.
